UNITED STATES PATENT OFFICE.

DON D. MILES, JR., OF SAN FRANCISCO, CALIFORNIA, ASSIGNOR TO BENJAMIN GOODWIN, OF SAN FRANCISCO, CALIFORNIA.

STARTER FOR INTERNAL-COMBUSTION ENGINES.

1,098,046.

Specification of Letters Patent. Patented May 26, 1914.

Application filed January 20, 1912. Serial No. 672,454.

To all whom it may concern:

Be it known that I, DON D. MILES, Jr., a citizen of the United States, residing at the city and county of San Francisco and State of California, have invented certain new and useful Improvements in Starters for Internal-Combustion Engines, of which the following is a specification.

The hereinafter described invention relates to automatic starters for internal combustion engines, and particularly to starters adapted to be used in connection with internal combustion engines as applied to automobiles, and to a type wherein air under compression is employed to start an air operated starting engine or motor and automatically connect the motor with the engine shaft to be started. After starting the engine the motor is converted into an air compressor, recharges the air supply reservoir which operates the motor, the air compressor after having recharged the air supply reservoir being automatically disconnected by the air pressure in said supply reservoir from the engine and permitted to remain idle until it is desired to again start the engine.

The invention has for one of its objects to provide a device which is light in weight, simple in construction, and positive and automatic in all of its operations.

Another object is to provide a motor which after starting the engine may be readily converted into a pump for recharging the air supply tank, without altering or changing any part of the starting engine but by simply changing the direction of the flow of air current within the motor.

With these and other objects in view, the invention consists in the novel combination of parts hereinafter fully described, illustrated in the accompanying drawings, forming a part of this invention, and pointed out in the claims hereto appended; it being understood that various changes in the form, proportions, size and minor details of construction within the scope of the claims may be resorted to without departing from the spirit or sacrificing any of the advantages of the invention.

To comprehend the invention reference should be had to the accompanying sheets of drawings, illustrating a complete con-

structed apparatus for successively carrying out my invention, wherein—

Figure 1 is a side elevation of my improved starting engine or motor as applied to an internal combustion engine of an automobile, disclosing one of the oscillating cylinders, the piston rods, the crank shaft and the connection therefrom to the clutch mounted on the drive shaft of the engine to be started, the means connected to the motor and clutch for throwing the same into and out of engagement, and the valve and operating means, and the air storage tank for controlling the operation of the motor. Fig. 2 is a longitudinal sectional view of my improved starting engine or motor when operated as a motor, disclosing the connection from the air storage tank, the oscillating valves carrying the cylinder and piston, the combined intake and exhaust ports in said valve, the valve controlled passages in the base of the motor for converting the same from a motor to a pump, the mechanism for automatically operating the clutch on the engine shaft, and the piston rods eccentrically mounted on the drive shaft for oscillating the said valves carrying the cylinders and pistons. Fig. 3 is a horizontal sectional view of my improved starter, taken on line 3—3 (Fig. 2) disclosing the transverse intake and exhaust ports in full lines, and in dotted lines the transverse communication between the intake ports and the longitudinal communication between the exhaust ports, the communication between the exhaust ports and the atmosphere and the longitudinal passage for admitting air to operate the means for connecting the motor with the engine to be started. Fig. 4 is a top plan view of my improved starter, showing the cylinders, piston rods, drive shaft, and the mountings for the same. Fig. 5 is a vertical sectional view of the preferred clutch, and the manner of mounting the same on the engine crank shaft. Fig. 6 is a broken top plan view disclosing the construction and mounting of the oscillating valves.

In the drawings, the numeral 1 designates a suitable base mounted on the frame of the vehicle and provided at one end with a suitable upwardly extending circular or ring-shaped portion 2, in each side of which

are adapted to be mounted disk-shaped valves 3 and 4, each being approximately of a width equal to one-half of the total width of the ring-shaped portion 2, and of a diameter approximately the same as the opening in said ring, the ring 2 providing a bearing for each of the valves, they being retained therein in any suitable manner, as disclosed in Fig. 6 of the drawings. The 5 ring is split transversely as at 2' and longitudinally as at 2" at its top, and provided with suitable means whereby the ring may be clamped together to take up any wear that may be occasioned by the working of 10 the valves, as disclosed in Fig. 4 of the drawings.

Mounted on the outer face of each of the valves 3 and 4 are cylinders 3' and 4', in which are slidably mounted pistons 3" and 4", from which extend suitable piston rods 5 and 6, the outer ends of which are adapted to be journaled to outwardly extending pins 7 and 8, arranged eccentrically one on each end of the shaft 9, rotatably supported in 25 suitably spaced upwardly extending bearings 10 and 11, positioned at the opposite end of the base 1 from the ring 2; the pins 7 and 8 being preferably arranged at an angle of 90 degrees from each other, about 30 the shaft 9, as in Figs. 1, 2 and 4 of the drawings. The piston rods being respectively connected at their ends to the pins 7 and 8, arranged about the shaft as above stated, it will be readily understood that the 35 valves are not in the same position or stroke of operation at the same time.

The motor base 1 is provided at its end adjacent the valves 3 and 4 with a longitudinally extending inlet passage 12, one 40 end of which communicates with an air supply reservoir 13, the normal capacity of which is approximately 150 pounds, and the other end communicates through a branch passage 14 with a transversely extending inlet passage 15 which is arranged directly 45 under the valves 3 and 4, and is adapted when the valves are oscillated into certain positions to register with channels 16 and 17 extending from the base of the valve, and 50 communicating at their upper ends with the opposite ends of the cylinder carried by the valve. The motor base is also provided adjacent the inner passage 15 with parallel 55 exhaust passages 18 and 19 arranged one on each side of the inlet passage 15, the passage 19 being connected to the passage 18 by a transversely extending passage 20, and the passage 18 opening to the atmosphere. The passages 18 and 19 will 60 be alternately in communication with their respective passages 16 and 17, when the other of said passages is in communication with the inlet passage 12. Thus when air is forced in one end of the cylinder to 65 operate the piston, the air contained in the

other is exhausted to the atmosphere, and from the above description it will be apparent that a double actuated piston is provided.

Communicating with the inlet passage 12 70 and extending longitudinally of the base 1 is a passage 15', the opposite end of which communicates with the inner end of an enlarged cylindrical chamber 19', in which is slidably mounted a piston 20' carrying a 75 piston rod 21 which extends through an opening in the end of the base 1. The passage 15' is provided in its upper surface with an opening 22, adapted under certain conditions to be closed by a ball valve 23. 80 A passage 24 is also provided in the base 1, and extends longitudinally thereof, one end of which communicates with the outer end of the cylindrical chamber 19', and the other end communicates with the opening 12; the 85 passage 24 being normally closed from communication with the opening 12, by a spring actuated valve 25, arranged in said passage, the tension of the spring being approximately 150 pounds, or the same as the normal 90 capacity of the air reservoir.

Mounted in a suitable opening extending transversely of the base 1, is a turn plug or rotary valve 26, provided with transversely extending parallel spaced ports 27 and 28, 95 which, when the valve handle 28' is in a downwardly inclined position, as in dotted lines in Fig. 2 of the drawings, the port 27 closes the opening to the atmosphere of the passage 18, and directs the flow of air therefrom through a by-pass 29, controlled by the ball valve 29', into the passage 12, and at the same time closes the passage of air from the passage 12 to the passage 15, this being when the device is operated as an air 100 compressor. The handle is normally held in a downwardly inclined position by the action of a coiled spring 29", one end of which is attached to the handle and the other to a stationary arm 29'.

When operated as a starting engine or motor, the valve handle 28' is moved to a horizontal position by the actuation of a foot pedal or lever 29' on the floor of the car, which raises the arm 28', which positions the port 28 in communication with the exhaust 18 and the atmosphere, and the port 27 in communication with the intake passage 12 and the inlet passage 15.

Any suitable connection between the motor and the engine to be started may be employed, the form disclosed in the drawings being merely for illustration.

Keyed to the shaft 9, between the bearings 10 and 11, is a suitable toothed sprocket 125 wheel 30 around which extends a suitable link chain 31, the other end of which extends around a suitable toothed wheel 32 loosely mounted on the crank shaft 33 of the engine. One face of the wheel 32 is 130

provided with an annular cone-shaped projection 34, which is adapted to be thrown into engagement with an overhanging flange 35, on the periphery of a disk 36, keyed to the crank shaft 33 of the engine. The wheel 32 and disk 36 are normally forced apart by the action of the coiled springs 33'.

The mechanism for throwing the two clutch members into engagement comprises 10 a lever 37 having an enlarged head portion 38, which loosely fits around the shaft 33, adjacent the hub of the wheel 32, and is provided with a flat face 39, adapted to lie in contact with the hub of the wheel 32, and 15 the opposite face of the head is provided with a cam surface 40, which, when the clutch members are separated lies in a cam groove 41 in a ring 42, loosely mounted on the shaft 33, one end of the ring extends to 20 and is carried by the frame of the car. The free end of the lever 37 is connected by a suitable bar 43 to the outer end of the piston rod 21 carried by the piston 20'.

The operation of the device is as follows:—The parts being assembled as in Fig. 25 1 and the air supply reservoir charged to its capacity and it is desired to start the starting engine or motor, the operator pushes the foot pedal 29⁴ which raises the handle 28⁷ 30 of the valve 26 against the tension of the spring 29², this permitting the air in the storage reservoir 13 to rush through the inlet channel 12 into the branch passage 14 through the opening 27 in the valve 26 and 35 into the inlet passage 15 in the base of the frame and is admitted into whichever opening 16 or 17 that is in communication with the passage 15, passes up through said opening and into the cylinder, forcing the 40 piston to reciprocate, which forces the air being compressed in the opposite end outwardly through the passage that is in communication with the exhaust passage, the pistons being thus operated rotate the shaft 45 9. The throw of the crank pins on the ends of the shaft 9 is so great that as the shaft rotates, the valves carrying the cylinders are oscillated sufficiently so that the port that was in communication with the intake 50 13 is now in communication with the exhaust, and the port that was exhausting is in communication with the intake. The ports of the valves 3 and 4 alternately registering with the intake and exhaust passages provide a continuously operated device. Upon 55 the admission of air under pressure into the inlet 15, a certain volume of air passes through the passage 15', raises the ball valve 23 to close the opening 22, enters the inner end of the chamber 19' forcing the piston 20' carrying the piston rod 21 outwardly. The outer end of the piston rod 21 being connected with the upper end of the cam lever 37, rotates the cam 40 out of the slot 60 41, thus forcing the loosely mounted wheel 65 42 carrying the chain 31 which is connected to the wheel 30, into engagement with the flange 35, and the drive shaft 33 of the engine is rotated by the starting engine or motor until the engine to be started starts 70 under its own power.

After the engine has been started by my improved starter, and is operating by its own power, the pressure is released from the foot pedal 29⁴ and the spring 29² draws 75 the handle of the valve into a downwardly inclined position, which closes the exhaust port 18 to the atmosphere, and also closes the passage from the branch 14 through 27 to inlet 15, but makes a direct passage from exhaust 18, through port 27 to passage 29, thus it will be noticed that the flow of air from the air supply reservoir to the motor is cut off and the starting engine or motor is now operated as a pump by the engine 80 85

The action of the pistons in the cylinders is the same as described before, but instead of being operated by air under pressure, air is drawn in through the opening 22 in the 90 passage 15' and in place of the exhaust air being forced to the atmosphere, it is directed through the port 27 in the rotary valve 26 into the passage 29 and into the air supply reservoir 13, the back flow therefrom 95 being checked by the ball valve 29'. After the tank 13 has been recharged to its normal capacity, which is regulated by the spring controlled valve 25, the compressed air as it is forced into the passage 12, displaces the valve 25 and air is forced through the passage 24 into the outer end of the chamber 19' forcing the piston 20' inwardly, which draws the lever inwardly, seating the cam 40 in the cam groove 41 and disconnecting 100 the wheel 32 carrying the chain 31 from the wheel 36, keyed to the shaft 33 stopping the operation of the starting engine until the foot pedal is again pushed downwardly and it is desired to start the engine. Upon 105 110 the initial starting of the engine any suitable means may be employed for throwing the clutch into operation for charging the air reservoir 13.

Having thus described the invention what 115 I claim as new and desire to secure by Letters Patent is:—

1. In a starter for explosive engines, the combination with an engine shaft, of an air actuated motor, connection between said 120 motor and engine shaft, a reservoir for air under pressure, a valve for admitting air from the air storage means to the air actuated motor, a piston actuated by the air under pressure for throwing into operative relation the connection between said motor and engine shaft, means for positioning said valve to cut off the flow of air from the air storage means to the motor and to admit air under compression from the motor to the air stor- 125 130

age means for recharging the pressure therein, and a valve actuated by the air in the air storage means attaining a given pressure for admitting air to said piston to operate 5 the same to throw into inoperative relation the connection between said motor and engine shaft.

2. In a starter for explosive engines, the combination with an engine shaft, of an air 10 actuated motor, direct connection between said engine shaft and the motor, a reservoir for air under pressure, a valve for admitting air from the air storage means to the air actuated motor, a piston actuated by the air 15 pressure against one surface thereof, and operated by the air pressure when admitted to operate the motor for throwing into operative relation the connection between the said motor and engine shaft, means for

positioning said valve to cut off flow of air 20 from the air storage means to the air actuated motor to convert the motor into a compressor and to admit air under compression from the compressor to the air reservoir for restoring the pressure therein, and a valve 25 operable upon the air in said reservoir attaining a given pressure for admitting air to the opposite surface of said piston to actuate the same for throwing into inoperative relation the connection between said 30 compressor and engine shaft.

In testimony whereof I have signed my name to this specification in the presence of two subscribing witnesses.
